UNITED STATES PATENT OFFICE.

ELMER M. SUMMERHAYS, OF HAMMOND, INDIANA, ASSIGNOR TO FREDERIC SCHAEFER, OF PITTSBURGH, PENNSYLVANIA.

BRAKE-ROD JAW.

1,405,877.

Specification of Letters Patent. Patented Feb. 7, 1922.

Application filed February 20, 1919. Serial No. 278,184.

To all whom it may concern:

Be it known that I, ELMER M. SUMMERHAYS, a resident of Hammond, in the county of Lake and State of Indiana, have invented 5 a new and useful Improvement in Brake-Rod Jaws, of which the following is a specification.

The invention described herein has for its object the provision of a brake rod jaw of 10 simple and cheap construction and which can be easily assembled with the brake rod. The invention comprises a brake rod jaw consisting of two parallel members connected at one end by a web which is adapted to 15 be engaged by a hook on the end of the brake rod, and provided with lugs extending laterally from the web and adapted to engage the body of the rod and prong of the hook to lock the latter in engagement with 20 the jaw. The invention is hereinafter more fully described and claimed.

In the accompanying drawing Fig. 1 is a plan view of my improved brake rod jaw, showing a portion of the brake rod in engagement therewith; Fig. 2 is a side elevation of the same; Figs. 3 and 4 are sectional views on planes indicated respectively by the lines 3—3 and 4—4, Fig. 2; Fig. 5 is a plan view of a form of blank adapted, by bending certain of the parts, to form the jaw; and Fig. 6 is a sectional view on a plane indicated by the line 6—6, Fig. 5.

While my improved jaw can be formed by any suitable means, as by casting or 35 forging, providing malleable metal is used in forming the casting, it is preferred to first form a blank from wrought metal by means of suitable dies by what is known as the blanking out method, the dies being so 40 shaped as to form a body of suitable shape by causing the metal to flow to the different parts of the matrices of the dies which are so formed that the excess of metal is distributed to those parts of the jaws subject- 45 ed to the greatest strains in the use of the same. These operations are well known in the art.

The dies employed in the blanking out method are constructed to form a blank as 50 shown in Fig. 5 and consisting of two portions 1 and 2 each having at one end a pin eye or opening 3 and having their opposite ends connected by a web 4. In the blanking process, concave seats 5 are formed in the 55 upper and lower sides of the web for the re-

ception, as hereinafter described, of the body 6 of the rod and of the prong 7 of the hook. The web on its opposite sides at its outer end is provided with lugs or wings 8 and 9, said wings lying in different planes and 60 extending from diagonally opposite edges of the extension of the web. After the blank has been stamped out and shaped as described, the parts or members 1 and 2 are, by any suitable means, bent to bring the 65 planes of their faces into parallelism and the centers of the eyes 3 into alignment, the lines of bend corresponding to and being coincident with the lines of junction of the web with the portions 1 and 2. It is preferred 70 that this bending operation should be effected in suitable dies as is well known in the art.

In connecting the jaws to the rod, the end of the rod is preferably first bent to almost 75 completely form the hook 7. To assemble the parts, the body 6 of the rod is placed in the upper seat 5 of the web of the jaws and the web 4 entered into the hook by a relative longitudinal movement, after which the 80 hook is fully closed onto the seat 5 in the underside of the web. After the parts have been assembled as described, the lugs 8 and 9 are bent in opposite directions, one around the body 6 of the rod and the other around 85 the prong of the hook 7, thereby firmly clamping both portions of the rod in the seats in the webs, and preventing the hook from opening and becoming disengaged end- 90 wise of the web.

It is preferred that the web portion 4 be made comparatively long in order that the rod and prong of the hook may have long bearing surfaces on the web, and have the eyes of the jaws in or approximately in 95 alignment with the line of draft, thus avoiding transverse strains.

I claim:

1. A brake rod jaw comprising parallel jaw members, a web connecting one end of said members and serving as means for engaging a hook on a brake rod, said web extending rearward beyond the jaw members and having channels in the opposite sides thereof adapted to receive the prong and body of a 100 brake rod hook, and lateral wings on said extension adapted to be bent around the prong and body of the brake rod hook to clamp them in the said channelled seats.
2. A brake rod jaw comprising parallel 110

jaw members connected by a web, said web extending rearward from the jaw members and having its opposite sides channeled to form seats for the prong and body of a 5 brake rod hook, and lateral wings on said extension adapted to be bent around the prong and body of the brake rod hook to clamp them in the said channels.

3. A brake rod jaw comprising parallel 10 jaw members, a web connecting the rear end of said jaw members and extending rearwardly therefrom in a plane perpendicular to the planes of the jaw members, the rearwardly extending portion having curved 15 channels in its opposite sides adapted to receive the prong and body of a brake rod jaw.

4. A brake rod jaw comprising parallel 20 jaw members, a transverse web connecting the base of said jaw members, said web lying in a plane perpendicular to the plane of the jaw members and extending rearwardly from the base of said members, seats formed in the opposite sides of the said 25 rearward extension and adapted to receive the prong and body of a brake rod hook,

and wings extending in opposite directions from the sides of the said rearward extension and adapted to be bent over the said prong and body of the brake rod hook where- 30 by to secure them in the said channels.

5. A wrought metal brake rod jaw comprising a forged blank having parallel jaw members extending from a connecting web portion, said connecting portion extending 35 rearwardly beyond the bases of the jaw members and having its opposite sides formed into receiving channels, and lateral wings extending from the sides of the said rearwardly extending web portion beyond 40 the bases of the jaw portions, the said forging being adapted to have the jaw members bent into parallel positions and the wing portion bent around the prong and body 45 portion of the brake rod hook seated in the said channels.

In testimony whereof, I have hereunto set my hand.

ELMER M. SUMMERHAYS.
